Inventor
Albert P. Worthington

By his Attorney *J. Edmunds*

UNITED STATES PATENT OFFICE.

ALBERT P. WORTHINGTON, OF LOS ANGELES, CALIFORNIA.

GRIP HANGER.

Application filed December 4, 1922. Serial No. 604,973.

To all whom it may concern:

Be it known that I, ALBERT P. WORTHINGTON, a citizen of the United States, residing at Los Angeles, in the county of Los Angeles and State of California, have invented certain new and useful Improvements in Grip Hangers, of which the following is a specification.

This invention relates to pumping apparatus, and relates more particularly to grip hangers.

The aims of this invention include the provision of a grip hanger of durable and sturdy construction for pivotally supporting suspension means for sucker rods or the like, and a hanger which is adapted to function with a minimum of friction and wear. Another object of this invention is to provide a grip hanger which may readily be secured on a walking beam against accidental displacement, and a hanger so designed that the rod suspension means may readily and easily be mounted on the hanger or be removed therefrom. Another object of this invention is to provide a grip hanger arranged to avoid harmful torsional, tensional and crystallizing strains. Other objects of this invention will be in part obvious and in part pointed out hereinafter.

It has heretofore been proposed to provide a hanger having a stem pivotally supported at the top on the upper side of a walking beam and having at its lower end, considerably below the beam, a head for supporting the rod suspension means. Such construction has been found to be fragile and subject under usage to torsional, tensional and crystallizing strains in consequence whereof the stem is apt to break and the hanger rendered useless.

In accordance with my invention, instead of suspending the supporting head for the rod suspension means from the end of a depending rod, I mount the supporting head directly upon and in pivotal anti-frictional association with a frame placed on the walking beam. The design is such that the cable, rope, or the like, of the rod supporting means passes over the head so as to bear downwardly thereon from above, thus tending to eliminate all torsional, tensional and crystallizing strains upon the hanger, while at the same time permitting with ease and freedom the desired pivoting of the rod suspension means with respect to the beam.

In order that a clearer understanding of

my invention may be had, attention is hereby directed to the accompanying drawings, forming a part of this application and illustrating one possible embodiment of my invention. Referring to the drawings, Fig. 1 is an end plan view of a hanger embodying my invention mounted on the end of a walking beam, with the cable (shown in fragment) of rod suspension means mounted on the hanger; Fig. 2 is a vertical sectional view taken on the line 2—2 of Fig. 1; and Fig. 3 is a top plan view of Fig. 1. Similar reference characters refer to similar parts throughout the several views of the drawings.

Referring to the drawings, the hanger includes a frame 1, preferably an integral, sturdy casting, having a base 2 arranged to rest substantially upon the top of a walking beam 3 of pumping apparatus, or the like, and to which it may be secured by bolts or screws 4. Arms or brackets 5 extend upwardly from base 2, meeting at a reinforced portion 6, the upper surface of which is indented to form a curved bearing surface 7 having an upwardly extending stop flange 8, at each end. For pivotal association with frame 1 I provide another hanger member 9, preferably semi-circular in shape, and of sturdy and durable construction, preferably being a metal casting; this member 9 having a peripheral rope or cable engaging groove 10 and a bearing surface 11, adapted to seat upon bearing 7 of the frame 1; and also having a recess 12 at each end of the bearing surface adapted to receive and interlock with one of the flanges 8 of the frame 1. Preferably, member 9 is provided with a cross-brace portion or member 13 which extends through an opening 14 provided centrally in frame 1.

When the parts have been assembled together in the above manner and the walking beam is operated, member 9 will pivot freely on frame 1 while moving the cable 15 of the rod supporting means up and down. Oil grooves 16 may be provided in bearing 7 to harbor a lubricant and to reduce friction. It is apparent that any downward pull of the cable 15 will be transmitted downwardly upon member 9 and also downwardly upon frame 1 and thereby upon the walking beam, and that no harmful torsional nor tensional strains, nor strains which would tend to create crystallization or breakage of the parts will be present. Meanwhile

member 9 is securely held against lateral displacement by means of interlocking flanges and recesses, and cable 15 is securely but removably held in groove 10.

6 The rod supporting cable, bent rod, rope, or the like, may readily and easily be placed on the hanger by placing the cable or the like in the groove provided therefor. The cable or the like may be removed as readily

10 and easily.

As many changes may be made in the above construction and as many different embodiments of this invention may be made without departing from the scope thereof, 15 it is intended that the matter contained in the above description or shown in the accompanying drawings be interpreted as illustrative and not in a limiting sense.

What I claim is:—

20 1. In a device of the character described, in combination, a frame adapted to rest upon a walking beam, a cable supporting member pivotally mounted on said frame, a bearing surface on said member engaging with a bearing surface on said frame, and interlocking recesses and flanges on said frame and member preventing relative lateral displacement of said frame and member.

25 2. In a device of the character described, 20 in combination, a frame adapted to rest

upon the upper face of a walking beam, and having a bearing surface disposed over said beam, a hanger member having a bearing surface engaging said bearing surface of said frame whereby said member is pivotally supported upon said frame, and a cable groove on said member disposed over said bearing surfaces, whereby downward pull exerted by said cable on said member is transmitted downwardly upon said frame 40 and said walking beam from above.

3. In a device of the character described, in combination, a frame having a base adapted to rest upon the upper face of a walking beam, and arms extending upwardly from said base, meeting at a reinforced portion over said base, an upwardly open semi-circular bearing surface on said reinforced portion, a hanger member having a bearing surface pivotally engaging said frame bearing surface, said member having a semi-circular grooved portion for receiving a cable disposed peripherally thereon and extending over said bearing surfaces, and a brace portion on said member extending through an opening in said frame between said arms.

This specification signed this 28th day of November, 1922.

ALBERT P. WORTHINGTON.
